(57) **CLAIM**

The ornamental design for a vehicle spoke wheel weight, as shown and described.

DESCRIPTION

FIG. 1 is a front, left, top view of a vehicle spoke wheel weight showing our new design.

FIG. 2 is an exploded view of the two identical halves constituting the vehicle spoke wheel weight of FIG. 1.

FIG. 3 is a top plan view thereof.

FIG. 4 is a bottom plan view thereof.

FIG. 5 is a front elevation view thereof, the rear elevation view being identical.

FIG. 6 is a left side elevation view thereof, the right side elevation view being identical.

FIG. 7 is a front elevation view of a first alternative embodiment thereof.

FIG. 8 is a front elevation view of a second alternative embodiment thereof; and,

FIG. 9 is a front elevation view of a third alternative embodiment thereof.

The broken lines form no part of the claimed design.

The vehicle spoke wheel weight is mounted to a spoke of a wheel of a vehicle for balancing the wheel.
